Alexander Kartveli, Huntington, N. Y., assignor to
Republic Aviation Corporation, Farmingdale,
N. Y., a corporation of Delaware

Application August 31, 1949, Serial No. 4,801

Term of patent 14 years

(Cl. D71—1)

To all whom it may concern:

Be it known that Alexander Kartveli, a citizen of the United States and a resident of Huntington in the county of Suffolk and the State of New York, has invented a certain new, original, and ornamental Design for an Airplane described and claimed in the following specification and shown in the accompanying drawings wherein:

Fig. 1 is a side elevation of an airplane embodying the present design with the landing gear retracted and the wing thereof in phantom;

Fig. 2 is a front elevation of the airplane as shown in Fig. 1; and

Fig. 3 is a perspective view from the front of the airplane shown in Fig. 1.

The characteristic features of my design reside

in the parts shown by means of full lines in the drawings.

What is claimed is:

The ornamental design for an airplane substantially as shown and described.

ALEXANDER KARTVELI.
